UNITED STATES PATENT OFFICE.

EDWARD N. ROWELL, OF BATAVIA, NEW YORK.

LABEL-CABINET.

1,151,402.

Specification of Letters Patent. Patented Aug. 24, 1915.

Application filed June 28, 1913. Serial No. 776,260.

To all whom it may concern:

Be it known that I, EDWARD N. ROWELL, a citizen of the United States, residing at Batavia, in the county of Genesee and State 5 of New York, have invented a new and useful Improvement in Label-Cabinets, of which the following is a specification.

My improvement relates to cabinets particularly adapted for holding stocks of druggist labels of various sizes, in such position that any labels required may be readily selected and removed one at a time. Many different sizes and shapes of labels are required by the druggist and, for convenience, 10 they should be kept where they are readily accessible and at the same time prevented from becoming soiled or curled and crumpled.

The object of my cabinet is to accomplish 20 these results in a simple and efficient manner and at the same time provide for readily adjusting the label holding devices so that labels of various sizes may be properly held.

A further object is to so construct the 25 cabinet as to form a suitable support and inclosure for the label holding devices and which may, if desired, be provided with an inclined top adapted to serve as a convenient writing desk where the labels may be 30 filled in.

In carrying out these objects I preferably construct a cabinet of wood or metal, open 35 at the front and provided with a slanting desk-like top. The end walls of the cabinet are adapted to support rods or bars extending parallel to the front of the cabinet and preferably so located as to support the label holding devices in an inclined position dipping toward the front.

40 The label holding devices are preferably flanged partitions which are adapted to be removably secured and supported upon rods or bars above referred to as provided for that purpose. In order that the cabinet 45 may be readily adapted to accommodate labels of varying widths, the flanged partitions or label holding devices are adjustable transversely along the rods or supports, thus enabling anyone to quickly adjust the dimensions of the several label compartments 50 to meet the requirements.

In carrying out my invention I have illustrated one form of cabinet in the accompanying drawings of which—

55 Figure 1 is a front elevation partially broken away at one corner; Fig. 2 is a cross

section on the line 2—2 of Fig. 1; Fig. 3 is a perspective view of one of the adjustable flanged partitions and Fig. 4 is a cross section of the same on line 4—4 of Fig. 3.

60

Referring to the drawings, 1 represents the cabinet which, as shown, is provided with a slanting top 2 which is adapted to serve as desk and may be used when filling in the prescription labels. The cabinet is 65 preferably open at the front and is provided with rods 3 extending parallel to the front of the cabinet and embedded or otherwise secured in the ends of the frame of the cabinet 1. The rods 3 are spaced apart 70 vertically a sufficient distance to accommodate labels of the sizes desired and as indicated in the drawings the rear rods are in a plane above the corresponding front rods 3 so that a plane passing through a front rod 75 and the corresponding rear rod will be at an angle to the base of the cabinet. The rods 3 are intended to support the label holding devices 4 which may be constructed of any suitable material but preferably are bent 80 up out of sheet metal as indicated in Figs. 3 and 4 of the drawings.

Each of the label holding devices 4, as shown, consists of a partition plate provided with lateral flanges 5 at the base thereof, 85 upon which the labels are adapted to be supported. The flanges 5 on each side of the partition extend forward slightly beyond the end of the partition and are bent up at 6 so as to serve to retain the bottom edges 90 of the labels in position. The lower or front end of the partition is provided with lateral flanges 7 which are adapted to prevent the labels from sliding out of the compartment formed by the flanges 5 and adjacent partitions. The flanges 7 are at an angle to but 95 do not extend quite to the flanges 5, thus leaving a space through which the labels may be withdrawn.

Each of the label holding devices 4 is provided with suitable clips or attaching devices for securing the same in position on the rods 3 in the cabinet. In the present instance the lugs 8 and 9 which are portions of the flanges 5 are bent downward and adapted 100 to partially encircle the rods 3 in the manner indicated in Fig. 2 of the drawings. The lugs or clips are adapted to fit the rods sufficiently snugly to hold the partitions in 105 any desired position of adjustment lengthwise of the rods. From the angular arrangement of the rods 3 for supporting each 110

shelf of label holding devices 4 it will be seen that the weight of the labels, set on end as indicated in the drawings, will tend to slide the same down the flanges 5 of the 5 label holding devices so that the front label in each compartment will rest against the lateral flanges 7 in position, to be readily removed when desired. To hold the labels erect and assist in feeding the same down 10 the flanges 5, suitable weights or following devices may be employed, the blocks 10 indicated in the drawings, being adapted for this purpose.

In adjusting the cabinet for use, the 15 flanged partitions 4 are supported on the rods 3 and adjusted longitudinally thereof so as to space adjacent partitions a sufficient distance apart to accommodate the labels it is desired to place in the cabinet. From the 20 construction of the holding devices or partitions, it will be seen that for narrow labels a large number of devices 4 can be mounted upon the rods and spaced at proper distance apart to accommodate a large number 25 of labels while if the labels are longer or of considerable size, it will not be necessary to use so many of the flanged partitions or label holding devices. This arrangement is adapted to make the cabinet flexible in that 30 all varieties of labels may be accommodated in the cabinet and only a single style or size of label holding device is required, thus reducing the cost of manufacture. Nevertheless it will be readily understood that 35 cabinets of any size may be made by simply increasing the length of the rods and the number of shelves or sets of rods employed and increasing the dimensions of the side walls of the cabinet, being careful to space the 40 rods apart the proper distance to accommodate the labels it is desired to place in the cabinet.

The operation of filling and adjusting the compartments in the cabinet will be readily 45 apparent from the description and from the drawings.

It will be seen that those using the cabinet can readily ascertain the number of labels 50 of any particular variety still in stock and hence the construction facilitates keeping track of the labels so that the stocks need not become exhausted before a new supply is ordered.

The labels may be readily removed as 55 desired by catching the bottom of the front label with the thumb and forefinger and drawing it forward and downward. The entire mass of labels back of the one being removed will then move forward so that the 60 next succeeding label will be in position to be likewise removed when desired. The turned up ends 6 of the flanges 5 are adapt-

ed to assist in retaining the lower ends of the labels while the front label is being removed and at the same time facilitate grasping the 65 lower edge of the label.

It will be understood that various modifications in the supporting devices and their arrangement as well as in the shape and specific construction of the adjustable label 70 holding partitions may be made without departing from the scope of the invention as set forth in the claims.

I claim:

1. In a label cabinet the combination of 75 partitions, flanges extending from the base thereof, flanges extending from the front end of said partitions in a plane at an angle to the base flanges, said flanges being adapted to support labels substantially vertical in 80 said cabinet, supports for said partitions, and means for securing the partitions to the supports and adapted to permit lateral adjustment of said partitions for accommodating labels of various sizes as desired. 85

2. In a label cabinet a partition member comprising a vertically disposed folded sheet metal plate, the fold forming the upper edge of the partition, integral flanges extending laterally from the base on each side thereof, flanges extending laterally from the front edge on each side thereof and means connected with and extending below the base flanges for removably and adjustably securing said partition in, said 95 cabinet.

3. In a label cabinet the combination with 100 a frame provided with supports, of partitions formed of sheet metal folded upon itself, the ends of the sheet being bent outward to form lateral flanges on each side of the base of the partition, the front edges being bent outward to form lateral flanges on each side at an angle to the base flanges and lugs projecting below said flanges for securing the partitions upon said supports. 105

4. In a label cabinet the combination with 110 a frame of transversely arranged supports, partitions transversely of said supports, each provided with a lateral flange on each side of the base thereof, lugs carried by said partitions for adjustably securing the same to said supports, and means at the front of said partitions, coöperating with said base flanges to maintain labels in a substantially 115 vertical position.

In testimony whereof, I have hereunto set my hand in the presence of two subscribing witnesses.

EDWARD-N. ROWELL
